(57) **CLAIM**

The ornamental design for a guitar stand with pick holder and cable holder, as shown and described.

DESCRIPTION

FIG. 1 is a top, front perspective view of a guitar stand with pick holder and cable holder, showing my design;

FIG. 2 is a right elevation view thereof, with the left elevation view being a mirror image of the right elevation view;

FIG. 3 is a top plan view thereof;

FIG. 4 is a front elevation view thereof;

FIG. 5 is a bottom plan view thereof; and,

FIG. 6 is a rear elevation view thereof.

The broken lines shown in the drawings depict portions of the guitar stand with pick holder and cable holder that form no part of the claimed design.
